(57) **CLAIM**

The ornamental design for a card for music instruction, as shown and described.

DESCRIPTION

FIG. 1 is a perspective view of the card for music instruction;

FIG. 2 is a right side view of the card for music instruction; FIG. 3 is a left side view of the card for music instruction; FIG. 4 is a back view of the card for music instruction; FIG. 5 is a front view of the card for music instruction; FIG. 6 is a top view of the card for music instruction; FIG. 7 is a bottom view of the card for music instruction; and,

FIG. 8 is a perspective view of the card for music instruction in an environment.

The two parallel broken lines at the bent tab portion depict perforations and form part of the claimed design. The three broken line openings depict the bounds of the claimed design, while all other broken lines are directed to environment.

1 Claim, 6 Drawing Sheets
